Primary Examiner — Katrina A Betton(74) *Attorney, Agent, or Firm* — Mark Murphey Henry(57) **CLAIM**

I claim the ornamental design for a trailer hitch, as shown and described.

DESCRIPTION

FIG. 1. is a perspective view of the trailer hitch.

FIG. 2. is a top view thereof.

FIG. 3. is a side view thereof.

FIG. 4. is a front view thereof.

FIG. 5. is a rear view thereof.

FIG. 6. is a bottom view thereof; and,

FIG. 7. is a reference view thereof in an environment use. The broken lines illustrate environmental subject matter that forms no part of the claimed design.
